OIL DISPENSER

John M. Young, Brooklyn, N. Y., assignor to
American Can Company, New York, N. Y., a
corporation of New Jersey

Application August 5, 1933, Serial No. 683,843

7 Claims. (Cl. 221—23)

This invention relates in general to a device for dispensing liquids from sealed containers and more particularly to an oil dispensing device adapted to open a sealed oil container filled with a measured charge of lubricating oil and dispense the contents.

The principal object of the invention is to provide the combination of a tamper-proof but readily frangible oil container adapted to cooperate with a simple, inexpensive funnel spout which fits over and makes liquid-tight locking engagement with projecting parts of the container, the funnel spout having means associated therewith for breaking through a wall of the container to produce an opening for dispensing the oil through the opening and through the spout into the filling opening of an automobile crank case.

An important object of the invention is the provision of such an oil container having locking projections or threads upon a part thereof which cooperate with like projections or threads upon the dispensing device, so that both container and device may be readily brought into intimate and liquid-tight locking engagement for the dispensation of the contents.

Still another important object of the invention is the provision of a funnel shaped dispenser adapted to lockingly engage in liquid-tight manner a double seamed end of a scored container and having a plunger adapted to break said score and produce a substantial pouring opening in said container.

Another important object of the invention is the provision of a novel method of dispensing branded or labeled motor oil in sealed, tamper-proof containers in an expeditious and economical manner, which method is designed to substantially prevent substitution and adulteration of the oils and to protect the ultimate consumer against any adulterated and inferior quality.

Numerous other objects and advantages of the invention will be apparent as it is better understood from the following description, which, taken in connection with the accompanying drawing, discloses a preferred embodiment thereof.

Referring to the drawing:

Figure 1 is a perspective view showing the dispensing device applied to an oil container of double seamed end construction;

Fig. 2 is a vertical cross sectional view taken through the device and container of Fig. 1 and showing the plunger after it has accomplished its score breaking function;

Fig. 3 is an enlarged, fragmentary, cross sec-

tional view of the lower part of the score breaking plunger and of the upper part of the double seamed and scored end of the container;

Fig. 4 is a fragmentary, cross sectional view of the device, showing the locking projections or threads adapted to engage the projecting parts of the double seam of the container; and

Fig. 5 is a cross sectional plan view taken along the lines 5—5 of Fig. 2.

The preferred embodiment of the invention illustrated in the drawings, presents generally a sheet metal container A and a substantially funnel shaped dispensing device B, also made of metal of somewhat heavier gauge than the container.

Preferably, the container A illustrates a size to hold an exact unit charge of lubricating oil, for example, a quart. It may, however, be made in a number of convenient sizes, for instance, half gallon, gallon or five quart size, or any other desired size. It comprises a cylindrical body 11, having a bottom end secured to it by means of a double seam 12, or in any suitable liquid-tight manner. A top end is secured to the opposite end of the body 11 by a like seam 13, and has a countersunk flat panel 14 provided with an annular score line 15, located just within the upwardly and outwardly projecting seam 13. The container is opened by breaking through the score line 15 and displacing the severed part of the panel 14 by means of the score breaking plunger hereinafter described in more detail.

The funnel shaped dispensing device B, preferably spun from seamless brass or copper tubing or cast from aluminum or other suitable metal, comprises a tubular body 16 of comparatively large diameter at its lower end and at its upper end gradually tapering into a comparatively small diameter dispensing element or spout 17, which, at its outer extremity, defines a restricted beveled opening 18. The body 16 adjacent its large diameter bottom, is cut away to provide a container engaging shoulder 21, having a recess 22, and thence terminates in a depending flange or collar 23.

In order to provide for a liquid-tight engagement between the funnel dispenser and the container, a sealing means such as an annular gasket 19, preferably of leather, rubber or other suitable material, is packed or crowded into the recess 22 of the shoulder 21.

The depending flange or collar 23 beneath the annular gasket 19 is provided at spaced intervals with elongated inwardly projecting locking threads 24 having inclined or beveled container 55

engaging upper faces 25. Four of these locking threads are preferably employed, leaving four unthreaded portions or recesses 26 between them.

To cooperate with these locking elements 24 on the collar 23 of the funnel dispenser B, corresponding locking projections or threads 27 are provided on the container A, by squeezing and projecting outwardly the metal of the top seam 13 at four spaced points about the periphery of the seam 13. These locking projections or threads 27 may be produced by a suitable die or squeezer jaw operation after the double seam 13 is formed in the usual manner and without disturbing the tightness of the seam 13.

15 The funnel dispenser B, at one side of the body 16, is formed with an apertured extension or boss 28 which provides a slide bearing for a score breaking plunger. The plunger comprises a square or rectangular stem 29 slidable within the 20 aperture of the boss 28 and having a reduced stud 31 adapted to threadedly engage within a threaded opening in a plunger handle 32. Attached at an inclined angle to the lower end of the stem 29, by means of a screw 33, is a score breaking shoe preferably made from tool steel and having a sharpened knife extension 34, curved to conform to the curve of the score line 15, and aligned relative to the container A to coincide with the score line 15 (Fig. 3). The body 35 of the shoe extends inwardly and upwardly from the knife extension 34 and terminates into a tapered nose.

The funnel dispenser B may be made in a number of different sizes and diameters to threadedly fit corresponding sizes and diameters of oil containers above referred to.

35 When a unit charge of oil of a certain requested brand is to be dispensed into the crank case of an automobile at the filling station, the attendant selects a filled, sealed and properly labeled oil container A of the desired size and brand and then inverts a corresponding size dispenser B over it in such a manner that the four seam projections 27 of the container coincide with the recesses 26 of the dispenser, and then lowers the dispenser over the container until the top edge of the seam 13 engages the gasket or packing 19 in the shoulder recess 22. He then rotates the dispenser B upon the container A in a clockwise direction, when the inclined upper faces 25 of the threads 24 catch 40 under the seam projections 27 and slide under them until the somewhat resilient gasket 19 has been tightly drawn down against the seam 13 and forms with the latter a liquid-tight seal which effectively prevents the escape of any oil between 45 such seal.

At this stage of manipulation the container, the dispenser and the score breaking plunger are all in the position illustrated in Fig. 3, with the score breaking knife 34 in exact alignment with the score 15. A slight downward pressure upon the handle 32 of the plunger causes the knife 34 to sever and break through an arcuate portion of the score 15. Further pressure brings the plunger into the position illustrated in Fig. 2, with the inclined 50 body 35 of the plunger shoe further severing and displacing the panel 14 along the score line 15 until the panel 14 is completely severed or remains hanging downwardly (as in Fig. 2) to a small unsevered part of the panel.

55 The container and funnel dispenser are then tilted to pouring position to dispense the oil through the opening created by the broken panel 14, through the spout 17, and into the filling neck of an automobile crank case or other place of deposit.

In order to permit the rapid draining of the oil an air vent hole 36 is provided in the body 16 of the dispenser, preferably opposite the boss 28.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. The combination in a liquid dispensing device, of a sealed liquid holding container having a threaded end portion, a funnel dispenser having a corresponding threaded portion adapted to interlock with said threaded container portion and plunger means depressible relative to said funnel and operable from without said dispenser for breaking a frangible part of the container and opening said container, said plunger means being mounted on and movable relative to said funnel dispenser.

2. A liquid dispensing device adapted for engagement with a sealed liquid holding container having a scored area for opening the container, said device having a funnel dispenser for engaging and enclosing said scored area and having means for sealing the top of the container, and means mounted on and axially movable relative to the funnel dispenser for severing said scored area and displacing it to unseal the contents of the container.

3. An oil delivery device, comprising a body adapted to make liquid-tight locking engagement with a seam of a sealed oil container, and a container wall fracturing means within said body and operable from without and depressible relative to said body to produce a pouring opening in said container along a provided weakening line of the container wall, whereby the oil may be dispensed through said device.

4. An oil delivery device, comprising a funnel shaped body adapted to telescopingly receive a sealed end of an oil container, said body being provided with threads adapted to make liquid-tight sealing engagement with corresponding threads on the container, and container wall fracturing means within said body and having a cutting edge near the container wall, and a wall-breaking shoe, and operable from without and depressible relative to said body to open said container.

5. A dispensing device for containers which have a wall adapted to be fractured to open the container and release the contents thereof, said device having in combination a dispensing element invertible over the container, and means within said element and axially movable relative thereto and to the container and operable from without the device so as to open the container and dispense the contents thereof, when the dispensing device and container are inverted in their engaged relation and said axially movable means has been moved in one direction to open the container.

6. A dispensing device for containers which have a wall adapted to be fractured to open the container and release the contents thereof, said device having in combination a dispensing element invertible over the container, and means housed within said element and axially movable relative thereto and to the container and operable from without said element so as to open the container and dispense the contents thereof, when the dispensing device and container are inverted.

in their engaged relation and said axially movable means has been moved in one direction to open the container, said dispensing device having a gasket adapted to engage and form a liquid-tight contact with the container.

7. A dispensing device for containers which have a wall adapted to be fractured to open the container and release the contents thereof, said device having in combination a dispensing element invertible over the container, and means

within said element and operable relative to and from without the same so as to open the container and dispense the contents thereof, when the dispensing device and container are inverted in their engaged relation, said dispensing device having a compressible sealing means near its bottom edge, and also having means to interlock with said container upon relative rotary movement of said device and container. 5
